UNITED STATES PATENT OFFICE.

FRANCIS A. HELIN, OF WATERTOWN, NEW YORK.

TWENTY-FOUR-HOUR CLOCK.

Application filed September 17, 1926. Serial No. 136,113.

This invention relates particularly to clocks of the twenty-four-hour type wherein the dial is provided with twenty-four graduations which are traversed by an hour 5 indicating pointer once in each twenty-four hours.

An object of the present invention is to provide a clock of this type having a dial with its hour graduations arranged in an 10 endless series and having a pointer driven by a clock movement to traverse continuously along said series, the dial graduations and their markings being designed to clearly 15 distinguish the diurnal hours from the nocturnal hours, and also the a. m. hours from the p. m. hours.

A further object of the invention is to provide a clock of simple structure having twenty-four hour graduations arranged in 20 an endless series and a pointer mechanism driven by a standard twelve-hour clock movement and adapted to move a pointer continuously in an endless path along said series of graduations.

25 In the drawings, Fig. 1 is a front face view of the clock; and

Fig. 2 a vertical section taken on the line 2—2 of Fig. 1.

Referring to the various parts of the clock 30 by numerals, 1 designates the clock casing. This casing is vertically elongated in form, rectangular at its lower end and semi-circular at its upper end in face view. The rear side of the casing is closed by a wall 35 2 and the front side is closed by a glass panel 3. A clock movement 4 is mounted within the upper curved end of the casing. This clock movement is of the standard twelve-hour type and has its hour arbor and its 40 minute arbor disposed concentrically with relation to the semi-circular upper end of the casing. The minute arbor is in the form of a slender central spindle 5 and the hour arbor is in the form of a sleeve 6 surrounding the minute arbor. Mounted upon the 45 hour arbor 6 and keyed to rotate with it is a driving sprocket wheel 7 of relatively large diameter. Adjacent the lower end of the casing 1 a stub shaft 8 is mounted upon the rear wall 2 and projects forwardly. This shaft 8 extends parallel to the two arbors and is disposed in the same vertical fore-and-aft plane with them. A follower sprocket wheel 9 is mounted to rotate upon 50 a journal portion 10 at the free end of the shaft 8. The follower wheel 9 is of the same

diameter as the driving wheel 7 and both are located in the same vertical plane. An endless chain 11 is trained around both wheels and extends in straight parallel lines 60 between them. The length of the chain 11 is equal to twice the circumference of the driving wheel 7.

Located inwardly of the glass panel 3, just in advance of the sprocket wheels and their chain, is a dial plate 12. The outer edge of this plate conforms in outline to the casing 1, being rectangular at its lower end and semi-circular at its upper end. The plate is secured within the casing in any suitable 65 manner. Centrally it is formed with a large, vertically elongated opening 13 conforming in outline to the course of the chain 11 and in register with it. Located within the opening 13 and disposed in the same plane 70 with the plate 12 is an inner dial and cover plate 14. The plate 14 has an outline similar to the opening 13 but slightly smaller in order to define a continuous slot 15 between the two plates and extending along the coarse 75 of the chain 11. The plate 14 is held in place with the plate 12 in any suitable way. In the present instance it is attached by screws 16 to posts 17 which project forwardly from the rear wall 2. At the center of its upper, curved end, the plate 80 14 is formed with an opening 18 through which the minute arbor 5 projects. A minute hand 19 is fixed to the outer end of the arbor at the front face of the dial plate. The chain 11 forms a carrier for an hour 85 pointer 20. This pointer is connected to one of the links of the chain in any suitable manner, as by a post 21 which projects through the slot 15. The pointer is directed outwardly toward the side of the clock face 90 and extends across the slot 15 at the front faces of the two dial plates.

The inner dial plate 14 is marked as at 22 to indicate minute graduations arranged in a continuous circular series concentric with the 100 minute arbor and surrounding the minute hand 19. In the present instance there are sixty of these graduations numbered in fives from "5" to "60". However, they may be numbered in a different order. The graduations are traversed by the minute hand and each revolution of the hand indicates the passage of one hour as in the case of a standard clock. The outer dial plate 12 is marked with two parallel continuous lines 23 extending entirely around the oblong opening 13 and parallel to the course of the chain 11.

These lines define the path of the outer end of the hour pointer 20 and the entire length of said path is graduated into twenty-four one-hour spaces by transverse marks 24. 5 The uppermost and the lowermost of the hour marks 24 upon the dial are located upon a vertical line extending through the centers of the wheels 7 and 9. These two marks are both numbered "12", the caption "Noon" 10 being placed over the upper mark and the caption "Night" placed beneath the lower mark. The graduation marks to the right of the vertical center line are numbered consecutively "1" to "11", downwardly from the 15 upper "12" mark. Those to the left of said line are numbered "1" to "11" upwardly from the lower "12" mark. The halves of the dial at the right and left of the center line are marked, respectively, p. m. and a. m. These 20 marks are placed approximately midway the vertical length of the dial just above the "6" marks at opposite sides thereof. The lines 23 are scored more heavily or more darkly below the "6" marks than above said marks, to graphically indicate that the graduations within the lower half of the dial represent the nocturnal hours and clearly distinguish them from the diurnal or daylight hours indicated upon the upper half 25 of the dial.

When the clock movement is running, the driver wheel 7 will be rotated continuously by the hour arbor 6 and said wheel will drive the carrier chain 11 and cause the hour 30 pointer 20 to traverse the continuous lines 23 and indicate the hours marked therealong. The minute hand 19 is adjusted with relation to the hour pointer 20 so as to accu-

rately indicate the minute time within the hour indicated by the pointer. The hour 40 dial and the moving pointer 20 represent graphically the movement of the sun relatively to the earth. A horizontal line through the two "6" marks may be considered the horizon. The path of the pointer 45 above this line represents the diurnal arc with its highest point at "12" (noon), and the path below the line represents the nocturnal arc with its lowest point at "12" (midnight). These points are thus logically 50 positioned upon the dial so that there is no danger of confusing them.

While I have shown and described a preferred embodiment of my invention, I reserve the right to make such changes in the 55 mechanism and in the arrangement and numbering of the dial graduations as will lie within the scope of the claim.

What I claim is:

A clock of the type set forth comprising 60 a clock movement including a continuously rotating hour arbor making one rotation in twelve hours; a driver wheel fixed to the arbor to rotate with it; an endless carrier trained around said wheel and guided in an 65 elongated course, the length of said carrier being equal to twice the circumference of the wheel; an hour pointer attached to the carrier; and an hour dial marked with twenty-four hour graduations arranged in 70 a continuous series extending around the course of the carrier and adapted to be traversed continuously by the hour pointer.

In testimony whereof I hereunto affix my signature.

FRANCIS A. HELIN.
